[57] CLAIM

The ornamental design of a wood holder for fireplace, as shown and described.

DESCRIPTION

FIG. 1 is a top, front and left side perspective view of a wood holder for fireplace showing my new design; FIG. 2 is an enlarged front elevational view thereof, the right side, left side and rear elevational views being identical to that shown; and,

FIG. 3 is an enlarged top plan view thereof, the bottom plan being the same as that shown.

The broken-line disclosure of a partial fireplace structure in FIG. 1 is for illustrative purposes only and forms no part of the claimed design.

FIG. 1

FIG. 3
